SLIDE FASTENER ACTUATOR

Warren B. Zern, 1016 N. Evans and Mineral St., Pottstown, Pa. 19464, and Charles H. Bode, New Hope, Pa.; said Bode assignor to said Zern

Filed July 29, 1966, Ser. No. 3,263

Term of patent 14 years

(Cl. D2—415)

FIG. 1 is a perspective view taken from one side of a slide fastener actuator showing our new design;

FIG. 2 is a perspective view of the slide fastener actuator of FIG. 1 taken from the opposite side thereof;

FIG. 3 is a sectional view taken along the lines 3—3 in FIG. 2;

FIG. 4 is a sectional view on an enlarged scale taken along the lines 4—4 in FIG. 2;

FIG. 5 is a sectional view on an enlarged scale taken along the lines 5—5 in FIG. 2;

FIG. 6 is a sectional view on an enlarged scale taken along the lines 6—6 in FIG. 2;

FIG. 7 is a sectional view on an enlarged scale taken along the lines 7—7 in FIG. 2;

FIG. 8 is an end view on an enlarged scale looking in the direction of the arrows 8—8 in FIG. 2;

FIG. 9 is a fragmentary elevational view partly in section of the lower end thereof of FIG. 3 with the actuator in closed position; and

FIG. 10 is a fragmentary perspective view of the lower end thereof of FIG. 1 of the actuator in closed position.

We claim:

The ornamental design for a slide fastener actuator, as shown and described.
